UNITED STATES PATENT OFFICE

98,823

DESIGN FOR A BAG OR ANALOGOUS ARTICLE

Clarence P. Beckman, Scarsdale, N. Y., assignor to Standard Brands Incorporated, New York,
N. Y., a corporation of Delaware

Application January 14, 1936, Serial No. 60,581

Term of patent 14 years

To all whom it may concern:

Be it known that I, Clarence P. Beckman, a citizen of the United States, residing at Palmer Avenue, Scarsdale, Westchester County, New York, have invented a new, original, and ornamental Design for a Bag or Analogous Article, of which the following is a specification, reference being had to the accompanying drawing, forming part thereof.

The different varieties of linings on the drawing are indicative of contrasting colors.

I claim:

The ornamental design for a bag or analogous article, as shown and described.

CLARENCE P. BECKMAN.
